UNITED STATES PATENT OFFICE.

HUGH T. NEWELL, OF PITTSBURGH, PENNSYLVANIA, ASSIGNOR TO CHOWNING REGULATOR CORPORATION, OF ELMIRA, NEW YORK, A CORPORATION OF NEW YORK.

MEANS FOR AUTOMATICALLY REGULATING THE BLAST COMPONENTS OF PRODUCERS.

1,267,443.

Specification of Letters Patent. Patented May 28, 1918.

Application filed July 19, 1917. Serial No. 181,567.

To all whom it may concern:

Be it known that I, HUGH T. NEWELL, a citizen of the United States of America, and a resident of Pittsburgh, Pennsylvania, have 5 invented certain new and useful Improvements in Means for Automatically Regulating the Blast Components of Producers, of which the following is a specification.

It has been heretofore proposed to maintain a constancy of the relative proportions of steam and air fed to gas producers by means of blast nozzles so constructed that within the range of the pressures of steam with which they are to be fed, such proportions in the blast will remain substantially fixed and constant. It has also been proposed to obtain the same constancy of proportion of air and steam in the blast by valves in the steam and air inlets to a nozzle 20 which, in itself, is not self-regulating as in the previous case. In order to vary automatically the total blast with the demand upon the producer, it has been further proposed that the pressure under which the steam is 25 admitted to the injector in the first case, and the valves controlling the admission of steam and air in the second case, shall be controlled by the pressure existing at the outlet side of the producer, so that the blast will be automatically decreased as the demands on the 30 producer fall, and at the same time, the proportion of air and steam in the blast shall remain constant. I propose to maintain this constancy of steam and air in the blast, and 35 to regulate the amount of the blast automatically by a new construction which permits the use of higher pressures in the blast than are obtainable in the schemes before referred to, permits a more rigorous and exact 40 regulation, and a wider variation in proportion of steam and air than is possible by such schemes.

To this end I propose to feed the air to the producer under a positive pressure created 45 by an air pump, the delivery of air from which is controlled by the speed of the pump, which in turn, is controlled by the pressure in the gas-main, and to also control by the pressure in the gas-mains, a valve in 50 the steam line fed from a source of constant steam pressure, so that the feed of the air and steam to the blast will be dependent, the one upon the speed of the fan, and the other upon the drop in pressure caused by

the steam control valve. My invention 55 therefore consists in the construction, combination and arrangement of the several parts of which it is composed, as will be hereinafter more fully described and claimed.

Referring to the accompanying drawing which is an elevation of a producer equipped with my invention, and in which corresponding parts are designated by corresponding marks of reference.—

The producer 1 may be of any approved construction, and is fed through the blast-pipe 2, the resultant gases being led from the producer through the gas-main 3. The blast pipe is fed by a suitable air pump 4 shown 70 as a centrifugal blower driven, by a variable speed motor 5. A suitable steam jet 6 is led into the air blast, and is connected with a suitable source 7 of steam under substantially constant pressure. The regulator 8 75 is preferably of the construction shown in the prior patent to Chowning, 1,066,252, of July 1, 1912, in which the position of the lever 9 is controlled by the pressure in the gas-main 3. This lever 9 is connected by the 80 linkage 10 with a valve 11 interposed between the source of constant steam pressure 7 and the steam jet 6, whereby such valve will be closed as the gas pressure in the main 3 increases. The lever 9 is also connected by the 85 link 12 with the arm 13 of a controller 14 in such a manner that as the gas pressure increases in the main, the controller will act to decrease the speed of the motor 5. Thus as the gas pressure falls in the main, due to 90 increased consumption or otherwise, additional steam will be admitted to the jet 6 and additional air will be supplied by the blower 4 to urge the gasification in the producer, and to build up the gas pressure. By properly selecting proper constants for the motor, and the valves the constancy proportions 95 of steam and air under these conditions can be assured.

Having thus described my invention what 100 I claim, and desire to secure by Letters Patent is,—

In an apparatus for securing a constancy in the proportions of steam and air forming the blast of a producer, and for automatically controlling the combined blast in accordance with the demand upon the producer, the combination with an air blast in-

take for the producer, of a blower supplying air thereto, and a steam jet supplying steam thereto, of means for varying the speed of rotation of the blower, a valve for controlling the pressure of the steam supplied to the steam jet, and means actuated by a variation in the pressure of the outlet side of the producer for controlling the speed of

the said motor, and the position of the said valve.

In testimony whereof I have signed my name.

HUGH T. NEWELL.

In the presence of—
C. W. SYPNIEWSKI.
